UNITED STATES PATENT OFFICE.

WILLIAM MUIR, OF NEW YORK, N. Y.

SIPHON-VALVE.

1,201,855.

Specification of Letters Patent. Patented Oct. 17, 1916.

Application filed December 21, 1915. Serial No. 67,999.

To all whom it may concern:

Be it known that I, WILLIAM MUIR, a citizen of the United States, and a resident of the city of New York, borough of Brooklyn, in the county of Kings and State of New York, have invented a new and Improved Siphon-Valve, of which the following is a full, clear, and exact description.

Among the principal objects which the present invention has in view are: to provide means for inaugurating the flow in a siphon in a flushing tank employing a siphon; to provide means for avoiding leakage in flushing tanks by perforating the lining thereof; and to provide an actuating mechanism easily operated and one that is durable and requires little attention after installation.

Drawings.—Figure 1 is a vertical cross section of a fragment of a flushing tank and a siphon head with which a flushing pipe is provided, the section being taken as on the line 1—1 in Fig. 2; Fig. 2 is a longitudinal section of the same, the section being taken as on the line 2—2 in Fig. 1; Fig. 3 is a detail view of a plunger head employed in connection with the present invention; Fig. 4 is a detail view of a loose piston head employed for elevating the water in the siphon head.

Description.—As seen in the drawings, a tank 9 is normally supplied with water 10 at an established level, such as indicated in Figs. 1 and 2 of the drawings. Any suitable and conventional means for supplying the water to the tank and maintaining the level of the same therein, may be employed. The tank 9 has fixedly mounted therein a gooseneck pipe 11, which has an end threaded 40 extension, the threads whereof are engaged by a locking nut 12, which permits a union for the gooseneck pipe 11, with the flushing tank of the system in which it is employed.

Depending from the short end of the pipe 11, is an inverted cylinder 13, the open lower end of which is disposed adjacent the bottom 14 of the tank, and establishes the lower water level therein. Water flows freely into the cylinder 13, to the high water level in the tank, and is held normally therein. In entering the cylinder 13, the water displaces the piston head 15, which normally rests in the plunger 16. The cylinder 13 is provided with open-ended guide tubes 17, which tubes extend through guide collars 18 on the plunger 16. The collars 18 are ta-

pered at their upper ends to serve as registering members to adjust the openings 19 in the disk 15, the said openings loosely fitting the collars 18 when normally disposed. The 60 collars 18 extend above the disk 15 when assembled, and serve as stops for the lift of the plunger 16 when elevated by the chains 20.

The chains 20 are spread as shown best in Fig. 1, and are connected at their upper ends by a cross bar 21, and at their lower ends by a spreader bar 22. The cross bar 21 is suitably connected with a rocking lever 23 of conventional arrangement and construction 70 and operated according to the usual practice. The spreader bar 22 is connected with and forms one of the median pivots of a lazy tongs 24. The lazy tongs 24 is pivotally attached by a bolt 25 with the bottom 75 14, and by a bolt 26 with lugs 27 dependent from and disposed adjacent to the center of the plunger 16, as shown best in Fig. 1 of the drawings.

From the foregoing it is obvious that if 80 the lever 23 is operated to lift the end thereof connected with the cross bar 21, the chains 20 are drawn up through the tubes 17, and the lazy tongs 24 is extended to lift the plunger 16 upward through the cylinder 13, 85 until arrested by the collars 18 engaging the top of the said cylinder. It is equally obvious that when the lever 23 is returned to its normal position, the weight of the plunger 16 and parts connected therewith causes the 90 lazy tongs 24 to collapse, the parts returning to their normal positions as shown in the drawings.

Operation.—When the parts are disposed as shown in the drawings, the water in the cylinder 13 is at the normal level and the disk 15 has been permitted to settle on the plunger 16 where it closes the elongated passages 28 formed in the said plunger. When the lever 23 is rocked, the spreader 22 is elevated, and the lazy tongs 24 connected with said spreader is rapidly extended to lift the plunger 16 and disk 15 supported on the same upward through the cylinder 13. The 95 water above the disk 15 is elevated thereby upward through the short extension of the gooseneck pipe 11 to fill said pipe. When the upward movement of the plunger 16 is arrested by the collars 18 engaging the top 100 of the cylinder 13, the established flow of 105 the water upward through the cylinder 13, lifts the disk 15 from the openings 28, and 110

thereafter maintains the disk in separated relation to the plunger 16. The water which now passes through the openings 28 in the plunger 16, flows through the central opening 29 in the disk to the gooseneck pipe 11, to maintain the flow therein and in the flushing system with which the same is connected. This operation continues until the water in the tank is exhausted to a level approximately that of the lower edge of the cylinder 13, when air entering the cylinder 13 and the gooseneck 11 operates to break the siphon established.

It is obvious that the collapsing operation 15 of the lazy tongs 24 and the lowering of the plunger 16 to its normal position, does not of necessity wait on the completion of the operation of the siphon and of the delivery 20 of the water from the tank 9 as above described.

The flow through the cylinder 13 is not sufficient to maintain or float the plunger 16 and parts connected therewith. It is sufficient, however, to partially float the disk 15 25 and prevent the settling thereof on the plunger.

Copies of this patent may be obtained for five cents each, by addressing the "Commissioner of Patents, Washington, D. C."

ger 16. When, however, the flow of the water has been suspended due to the breaking of the siphon, the disk 15 is permitted to settle upon the plunger 16, the tapered ends of the collars 18 operating to guide the 30 disk 15 to its normal position.

Claim:

A siphon, the short leg of which comprises an open-ended inverted receptacle; a plunger reciprocatively mounted therein, 35 said plunger having open passages therethrough; means for closing said passages when said plunger is moved toward the delivery end of said receptacle; and means for lifting said plunger, said means embodying 40 a lazy tongs disposed in line with the axis of and below said receptacle for moving said plunger toward the delivery end of said receptacle at a rate of movement relatively greater than the movement of said lever.

WILLIAM MUIR.
